GOLF EXERCISER

Bernays Johnson, Little Falls, N. J.

Application August 2, 1940, Serial No. 349,480

17 Claims. (Cl. 273—35)

The present invention is concerned with a golf practicing device and specifically is directed to a golf chipping and putting game and the objects, advantages, and salient functional and structural features thereof will be apparent from the following detailed specification considered in the light of the accompanying drawings wherein:

Fig. 1 is a perspective view of the golf game or exerciser according to the invention.

Fig. 2 is a transverse sectional view on the line 2—2 of Fig. 1.

Fig. 3 is a plan view of a golf practicing device or exerciser, shown partly in section.

Fig. 4 is a sectional view on the line 4—4 of Fig. 1.

Fig. 5 is a broken and sectional view of one of the standards and the rotary support for one of the wings of the back stop.

Fig. 6 is an enlarged vertical elevational view on the line 6—6 of Fig. 3 showing the outer ring of the vibratory golf ball deflector unit seated on the upper face of the hopper.

Fig. 7 is an inside view of the golf deflector unit taken on the line 7—7 of Fig. 3.

Fig. 8 is an inside view on the line 8—8 of Fig. 3.

Fig. 9 is a sectional view on the line 9—9 of Fig. 3, and

Fig. 10 is a view taken on the line 10—10 of Fig. 3, illustrating one of the webs of the vibratory spider secured to the concentric rings or ball deflector unit.

The golf game according to the invention is generally denoted 10 and embodies a golf deflecting unit in the form of a plurality of concentrically arranged relatively thin sheet metal rings 11, 12 and 13 having their lower ends fixedly secured to radially arranged and spaced webs or arms 14 characterizing a spider.

Each of the concentric rings is provided with spaced strengthening ribs 15 and 16 and the turned over flanges 17 and 18 for reinforcing the upper and bottom annular edges thereof and for purposes of specification webs 14 together with the spaced annular members or rings 11, 12 and 13 may be considered as a golf deflecting unit or chassis having a four point support in respect to the inclined sheet metal hopper 19 and thus the spider is completely spaced from any part of the hopper although suspended therein in spaced relation to the rim thereof. In this connection it will be observed that the rim 20 of the hopper 19 is substantially square shaped having its four upstanding sides provided with the turned in flanges 21 interrupted by gaps 22, thus leaving

four upper faces or seats 23 on which the four lower portions 24 spaced ninety degrees apart of the outer ring 11 are seated and for permanently holding the outer ring 11 to the rim 20 of the hopper, metal strips 25 are employed, these strips being welded or soldered to the sides of the rim 20 of the hopper and to the lower spaced portions 24 of the large outer ring 11. However at the front part of the outer ring 11 two metal strips 25 of the character referred to are utilized 10 and these straddle the opening 26.

Appropriately fixed to diametrically disposed portions of the outer ring 11 are the spaced baffles or wings 27 and these have their forward portions 28 fastened by bolt and nut means 29 to 15 the upstanding sides 30 of the inclined and hollow chute 31 having the inclined baffle wall 32 integral with sides 30 but extending appreciably below the upper edges thereof.

Sides 30 of the chute 31 constitute spacer means 20 for the angle irons or ball guide rails 32 having their rear ends fastened to the sides 30 and at one side of one of the rails a golf ball supply receptacle 33 is provided. This receptacle has an opening 34 in which return conduit 35 is fitted. 25

The conduit is disposed at an incline and has connected thereto the hollow elbow 36 carried by the supply conduit 37 directly communicating with the eccentrically disposed opening 38 in the pyramidal or dish shaped base 39 of the hopper 30 and for purposes of clearness base 39 may be said to comprise the four tapering and inclined sides 40, 41, 42 and 43.

The hopper 19 is held in an inclined relation by the spaced legs 44 and 45 fixedly sustained 35 by the rim 20 of the hopper. The rear end of the hopper is also provided with the fixed and spaced loops 46 through which is threaded the cross bar or horizontal rod 47 detachably secured to the spaced bushings 48 threadably carried by 40 the spaced vertical standards or supports 49 having their lower ends disposed in couplings 50.

Rotatably journaled in the spaced nipples or bushings 48 are the lower portions 51 of the L shaped standards 52 each of which fixedly carry 45 a stop ring 53 to limit the insertion of the lower portions 51 into the nipples 48.

The arms 54 of the rotatable L shaped standards 52 threadably receive the loop or socket 55 of the wings 56 of the cloth back stop 57 which has a lower intermediate part 58 removably draped over the rear flanges 21 of the hopper, thus causing any balls striking the intermediate part of the back stop to fall into the hopper and 55

eventually return through the conduit means by gravity to the supply receptacle 33.

- Since the upper standards 52 are rotatable the wings of the back stop may be desirably adjusted to any convenient angle relative to the hopper. Also since the back drop support consists of adjustable and detachable parts, it may be readily knocked down or disassembled and thereafter reassembled quickly when desired.
- Moreover, the wings 56 of the back stop include the superimposed pockets 59 and 60, either of which can readily trap the golf balls, the upper pocket 59 (Fig. 4) having an opening at the lower part thereof leading into the companion lower pocket 60, thus balls trapped by pockets 59 fall directly into the lower pockets.

In operation a golf ball 61 is taken out of the receptacle and put on the ground and placed between the rails 32 after which a suitable golf stick is employed for lifting or chipping the ball preferably into the smallest ring 13 for scoring purposes considered as counting three points. If such be accomplished a bell 61 usually issues an audible signal for the bell is generally struck when the ball in flight comes within the confines of the ring 13.

Where the ball enters the gap between rings 13 and 12, two points may be considered as scored by the operator. If within the gap between the outer ring 11 and the intermediate ring 12, one point may be counted. In case the ball strikes one of the wings of the back stop and falls into any of the pockets 60, one half of a point may be counted.

The bell 61 is carried by an offset arm 62 secured to the inner ring 13 and by means of the inclined relation of all of the concentric rings, the balls when striking the latter deflect downward and fall into the hopper and ultimately automatically return the supply receptacle 33.

The sheet metal nested and concentrically arranged rings 11, 12 and 13 together with the arms 14, in fact may be considered as sustained merely by a four point support namely, the four rectilinear bearing surfaces 23, on the four rectilinear sides of the hopper and consequently, in practice, it has been discovered that when a ball strikes any of these rings, it is to become "deadened," that is it will not bounce outwardly of the rings, and instead it is deflected inwardly and falls downwardly into the hopper. This is due to the fact that when the ball hits any of the concentric rings, the chassis oscillates slightly, or for the lack of a better expression, trembles or shivers, causing the ball to be deadened, thus falling as desired into the hopper. This deadening effect on the ball is also carried into effect by the inclined wall 32' of the chute 31 since the latter is hollow as shown, hence preventing undesirable bouncing of the ball when striking wall 32' having its highest portion arranged or sustained against the front and lower side of the hopper as shown.

In the matter of the wings 27, these aid to prevent spillage of the ball in a direction away from the hopper and thus cause the ball to fall into the hopper. As far as the flanges 21 are concerned, these perform the important duty of preventing the ball from spilling out of the hopper after having been cast therein by wings 27 or by the vibratory chassis. The front opening 26 is utilized in the case of putting without creating any lift to the ball. Where the ball enters this opening, it may count as five points.

While the invention has been specifically de-

scribed in detail, it is to be understood that it is not limited to specific details described but it is capable of other adaptations and modifications within the scope of the appended claims.

I claim:

1. In combination, an inclined hollow hopper having a relatively large opening at the upper end thereof, a vibratory spider suspended at said opening and completely spaced from any part of said hopper, a plurality of nested but spaced rings secured to said spider, rectilinear bearing means for sustaining one of said rings only, inclined chute means disposed against said hopper, and wings connected to said last mentioned ring and said chute means. 10

2. In combination, an inclined hopper, a vibratory spider within and completely spaced from any part of said hopper, a plurality of nested but spaced rings secured to said spider, bearing means on said hopper for sustaining spaced portions only of the outside ring of said plurality, and chute means connected to said hopper. 20

3. In combination, an inclined hopper, a vibratory spider within and completely spaced from any part of said hopper, a plurality of nested but spaced rings secured to said spider, bearing means on said hopper for sustaining spaced portions only of the outside ring of said plurality, inclined chute means connected to said hopper, and spaced guide means connected to said chute means. 25

4. In combination, an inclined hopper having a rim, a vibratory spider within said hopper and completely spaced from any part of said hopper, a plurality of nested but spaced rings secured to said spider, spaced bearing means on the sides of said rim for sustaining spaced curved portions only of the outside ring of said plurality, chute means connected to said hopper, flanges extending from said rim and inwardly overhanging said hopper, a receptacle, and conduit means connected to said hopper and said receptacle. 30

5. In combination, an inclined hopper having a rectangularly shaped rim, a vibratory spider within said hopper and having a plurality of divergent arms completely spaced from any part of said hopper, a plurality of nested but spaced relatively thin rings secured to said arms, rectilinear and spaced bearing means on the sides of said rim for sustaining spaced curved portions only of the outside ring of said plurality, chute means connected to said hopper, flanges extending from said rim and inwardly overhanging said hopper, a receptacle, and conduit means connected to said hopper and said receptacle. 45

6. In combination, an inclined hopper having a peripheral rim, a vibratory ball deflecting unit comprising a spider completely spaced from any part of said hopper and a plurality of nested but spaced rings secured to said spider, rectilinear and spaced bearing means on the sides of said rim for sustaining spaced curved portions only of the outside ring of said plurality, chute means connected to said hopper, flanges extending from said rim and inwardly overhanging said hopper, a receptacle, and conduit means connected to said hopper and said receptacle. 60

7. In combination, an inclined hopper having an upstanding rim, a vibratory ball deflecting unit comprising a spider substantially within said rim and completely spaced from any part of said hopper, a plurality of nested but spaced rings secured to said spider, spaced bearing means on the sides of said rim for sustaining spaced curved portions only of the outside ring of said plurality, 70

- inclined chute means connected to said hopper, flanges extending from said rim and inwardly overhanging said hopper, a receptacle, and conduit means connected to said hopper and said receptacle.
8. In combination, an inclined hopper having a rim, a spider within but spaced from said hopper, a plurality of nested but spaced rings secured to said spider, spaced bearing means on the sides of said rim for sustaining spaced curved portions only of the outside ring of said plurality, chute means connected to said hopper, flanges extending from said rim and inwardly overhanging said hopper, a receptacle, conduit means connected to said hopper and said receptacle, and a backstop disposed at the rear of said hopper and having swingable wings adapted to be disposed angularly in respect to the sides of said hopper.
9. In combination, an inclined hopper having a rim, a spider within but spaced from said hopper, a plurality of nested but spaced rings secured to said spider, spaced bearing means on the sides of said rim for sustaining spaced curved portions only of the outside ring of said plurality, inclined chute means connected to said hopper, flanges extending from said rim and inwardly overhanging said hopper, a receptacle, conduit means connected to said hopper and said receptacle, and a backstop disposed at the rear of said hopper and having swingable wings adapted to be disposed angularly in respect to the sides of said hopper.
10. In combination, an inclined hopper having a rim, a spider within but spaced from said hopper, a plurality of nested but spaced rings secured to said spider, spaced bearing means on the sides of said rim for sustaining spaced curved portions only of the outside ring of said plurality, chute means connected to said hopper, corner flanges extending from said rim and inwardly overhanging said hopper, a receptacle, ball conduit means connected to said hopper and said receptacle, a supporting frame at the rear of said hopper, spaced sockets carried by said frame, rotatable arms guided in said sockets, and a backstop carried by said frame and said rotatable arms.
11. In combination, an inclined hopper having a rim, a spider within but spaced from said hopper, a plurality of nested but spaced rings secured to said spider, spaced bearing means on the sides of said rim for sustaining spaced curved portions only of the outside ring of said plurality, an inclined hollow chute means connected to said hopper and having an inclined baffling plate, flanges extending from said rim and inwardly overhanging said hopper, a receptacle, conduit means connected to said hopper and said receptacle, and a backstop disposed at the rear of said hopper and having laterally extending wings, and means for rotatably supporting said wings.
12. In combination, an inclined hopper having a rim, a spider within but spaced from said hopper, a plurality of nested but spaced rings secured to said spider, spaced bearing means on the sides of said rim for sustaining spaced curved portions only of the outside ring of said plurality, an inclined rectilinear plate connected to said hopper, flanges extending from said rim and inwardly overhanging said hopper, a receptacle, conduit means connected to said hopper and said receptacle, a backstop disposed at the rear of said
- hopper and having laterally extending wings, bearing means for rotatably sustaining said wings, and communicating ball trapping pockets carried by said wings.
13. In combination, a hollow hopper having a bottom wall and an upper peripheral rim, a vibratory spider suspended substantially within said rim and completely spaced therefrom and said wall, a plurality of nested and spaced members secured to spaced portions of said spider, and spaced bearing means on said rim, the outer member only of said plurality having spaced portions only sustained by said bearing means and remaining portions thereof spaced from said rim and wall.
14. In combination, a hollow hopper having an inclined bottom wall and an upper peripheral rim, a vibratory spider suspended substantially within said rim and completely spaced therefrom and said wall, a plurality of nested and spaced and substantially concentric rings secured to spaced portions of said spider, and spaced bearing means on said rim, the outer ring only of said plurality having spaced portions only sustained by said bearing means and remaining portions thereof spaced from said rim and wall.
15. In combination, a hollow hopper having a bottom wall and an upper peripheral rim, a vibratory spider suspended substantially within said rim and completely spaced therefrom and said wall, a plurality of nested and spaced ball deadening members secured to spaced portions of said spider, spaced bearing means on said rim, the outer member only of said plurality having spaced portions only sustained by said bearing means and remaining portions thereof spaced from said rim and wall.
16. In combination, a hollow hopper having a bottom wall and an upper peripheral rim, a vibratory spider suspended substantially within said rim and completely spaced therefrom and said wall, a plurality of nested and spaced and relatively thin metal members secured to spaced portions of said spider, spaced bearing means on said rim, the outer member only of said plurality having spaced portions only sustained by said bearing means and remaining portions thereof spaced from said rim and wall, an inclined chute adjacent said hopper, side wings connected to said chute and closely straddling said outer member, and spaced ball guide means adapted to be connected to said chute.
17. In combination, a hollow inclined hopper having a bottom wall and an upper peripheral rim, a vibratory spider suspended substantially within said rim and spaced therefrom and said wall, a plurality of nested and spaced and substantially concentric rings secured to spaced portions of said spider, spaced bearing means on said rim, the outer ring only of said plurality having spaced portions only sustained by said bearing means and remaining portions thereof spaced from said rim and wall, flanges at the corners of said rim, a receptacle, conduit means connected to said wall and receptacle, an inclined chute adjacent said hopper, side wings connected to said chute and straddling said outer ring, and spaced rails associated with said chute.

BERNAYS JOHNSON.
